UNITED STATES PATENT OFFICE.

JAMES THORNTON GREELEY, OF NASHUA, NEW HAMPSHIRE.

CLINICAL-THERMOMETER HOLDER.

1,406,373.

Specification of Letters Patent. Patented Feb. 14, 1922.

Application filed August 27, 1920. Serial No. 406,358.

To all whom it may concern:

Be it known that I, JAMES T. GREELEY, a citizen of the United States, residing at Nashua, in the county of Hillsborough, and 5 State of New Hampshire, have invented new and useful Improvements in Clinical-Thermometer Holders, of which the following is a specification.

This invention is an improvement on a 10 thermometer casing or holder of the type disclosed by my Patent No. 1,152,503, dated September 7, 1915.

Said patented holder comprises an elongated tubular casing, closed at one end and 15 provided at its opposite end with a detachable confining member, adapted to releasably confine a thermometer in the casing, an annular valve seat within the casing, a valve formed to close on said seat to entrap a sterilizing liquid in the closed end portion of the 20 casing, and also formed to engage and be moved toward the closed end by a thermometer inserted in the casing, and a spring interposed between the valve and the closed 25 end of the casing, to hold the valve yieldingly against the seat.

Heretofore the valve seat has been fixed within the casing, and the construction has 30 been such that the operations of inserting and changing the liquid and cleaning the interior of the casing, have been attended with considerable difficulty.

The present invention has for its object 35 to facilitate said operations, by providing a valve seat, which is removable endwise from the open end of the casing when the confining member is removed, thus permitting the removal of the valve and spring through said open end, leaving the casing 40 vacant, and in condition to be conveniently emptied of liquid, cleansed and recharged.

The invention is embodied in the improvements which I will now proceed to describe and claim.

45 Of the accompanying drawings forming a part of this specification,—

Figure 1 is a longitudinal section of a thermometer-holder embodying the invention, and a side elevation of a thermometer 50 inserted therein.

Figure 2 is a view similar to Figure 1, the thermometer being removed.

Figure 3 is a view similar to Figure 2, the confining member at the open end of the 55 casing being removed.

Figure 4 is a longitudinal section of the casing, the valve seat, valve and spring being removed.

Figure 5 is a side view of the outer end portion of the thermometer shown by 60 Figure 1.

Figure 6 is a fragmentary sectional view, showing a modification.

The same reference characters indicate the 65 same parts in all of the figures.

My improved holder includes an elongated tubular casing, closed at one end and open at the opposite end, the casing being preferably composed of an inner tubular portion 12, of glass, and an outer tubular portion 13, of metal, projecting from the open end of the inner portion 12, and internally screw-threaded at 14.

With the said portion is engaged a confining member 15, which is preferably annular 75 and provided with an external thread engaging the internal thread 14, and with an internal thread 16 (Figure 2), adapted to engage an external thread 17 on a clinical thermometer 18.

19 represents a removable inner tube having a sliding fit on the internal surface of the casing, and composed of suitable yielding or compressible material, such as relatively soft vulcanized rubber. The inner 80 end of the tube 19 constitutes an annular valve seat 20. The outer end of the inner tube is releasably confined in the casing by the confining member 15.

21 represents an annular valve formed to 90 close on the seat 20 to entrap liquid in the closed end portion of the casing. Said valve is also formed to engage the tip of the thermometer 18, the tip-engaging portion of the valve being preferably a cup 22, 95 formed integral with the valve.

23 represents a spring interposed between the valve and the closed end of the casing, to hold the valve yieldingly against the seat 20.

The inner tube 19 is removable endwise 100 from the casing, when the confining member 15 is removed, the removal of said member exposing the outer end of the tube, so that the latter is free to be withdrawn from the casing.

To facilitate the withdrawal of the inner tube, I make the spring 23 sufficiently strong to partially project the inner tube from the casing, as shown by Figure 3, when the confining member is removed, the outer end 110

of the inner tube being thus held in position to be readily grasped and withdrawn.

The withdrawal of the inner tube permits the withdrawal of the valve 21, and the 5 spring 23, leaving the casing vacant, as shown by Figure 4. The casing is thus adapted to be sufficiently charged with a sterilizing liquid, and to be emptied of a previous charge, which has become contaminated, and to be conveniently cleansed when 10 emptied.

The confining member 15, when in place, 15 confines the inner tube 19, as shown by Figure 2, so that when the thermometer is removed, the valve 21 entraps the liquid in the inner end portion of the casing. When 20 the thermometer is inserted, as shown by Figure 1, some of the liquid passes above the valve and contacts with the thermometer.

Figure 6 shows a confining member 15^a, substitute for the member 15, said member 15^a being closed and adapted to bear on the outer end of the thermometer 18, the latter having no external screw thread.

25 I claim:

1. A thermometer-holder comprising an elongated tubular casing, closed at one end and provided at its opposite end with a detachable confining member, adapted to releas-

ably confine an inner tube and a thermometer 30 in the casing; a removable inner tube having an annular valve seat, said tube being a sliding fit in the casing and being releasably confined therein by said member, a valve formed to close on said seat to entrap liquid in the 35 closed end portion of the casing, and also formed to engage a thermometer inserted in the casing, and a spring interposed between the valve and the closed end of the casing to hold the valve yieldingly against the 40 seat, the inner tube being removable endwise from the casing when the confining member is removed.

2. A thermometer casing substantially as 45 specified by claim 1, the force of said spring being sufficient to partially project the said inner tube from the casing when the said confining member is removed, and thereby facilitate the removal of the tube.

3. A thermometer casing substantially as 50 specified by claim 1, said detachable confining member being annular and externally threaded to engage an internal thread on the casing, and internally threaded to engage an external thread on a thermometer.

55 In testimony whereof I have affixed my signature.

JAMES THORNTON GREELEY.
